UNITED STATES PATENT OFFICE.

WILLIAM H. KELLEY, OF READING, PENNSYLVANIA.

LUG-STRAP FOR PICKER-STICKS.

1,160,903.

Specification of Letters Patent. Patented Nov. 16, 1915.

Application filed November 14, 1914. Serial No. 872,190.

To all whom it may concern:

Be it known that I, WILLIAM H. KELLEY, a citizen of the United States, and a resident of Reading, in the county of Berks and State of Pennsylvania, have invented a new and Improved Lug-Strap for Picker-Sticks, of which the following is a full, clear, and exact description.

The invention relates to looms and its object is to provide a new and improved lug strap for picker sticks arranged to permit of convenient adjustment up or down on the stick for exerting more or less power, to securely hold the lug strap in the adjusted position and to allow of fitting the lug strap on sticks of different width and without weakening the stick by holes, notches and the like.

In order to accomplish the desired result, use is made of sweep straps provided with a pivoted striker adapted to engage the outer edge of the picker stick, an abutment fixed between the outer ends of the said straps for the striker to abut against, and a spring connecting the striker with the abutment. Use is also made of a clamping block adjustably secured to the picker stick and connected by links with the sweep straps, the said clamping block being provided on its edges with projecting spurs adapted to embed themselves in the picker stick, the clamping block having an aperture therethrough to one side of the median line for the passage of a pin forming part of the clamp to allow of reversing the clamping block and fitting the same on picker sticks of different width.

A practical embodiment of the invention is represented in the accompanying drawing forming a part of this specification, in which similar characters of reference indicate corresponding parts in all the views.

Figure 1 is a side elevation of the lug strap as applied to a picker stick and showing the striker out of engagement with the picker stick; Fig. 2 is an edge view of the same; Fig. 3 is a side elevation of the lug strap as applied to the picker stick and showing the striker in engagement with the picker stick, parts being shown in section; and Fig. 4 is an enlarged sectional plan view of the clamp, the section being on the line 4—4 of Fig. 1.

To the outer side of a picker stick A of the usual construction is clamped a clamping block B by the use of a clamp C, preferably in the form of a yoke C' straddling the picker stick and engaging a pin D extending

transversely through the clamping block B. The clamp C has threaded therein a set screw E which bears against a washer E' slidable on the yoke C' and bearing on the inner edge of the picker stick A, as will be readily understood by reference to the drawings. The clamping block B is provided with spurs B' having their pointed ends projecting at both edges of the clamping block so that the block can be reversed, and in either position the projecting points of the spurs engage the material of the picker stick A when screwing up the set screw E to cause the points to embed themselves in the material and thus hold the block B against accidental shifting on the picker stick A. By reference to Figs. 3 and 4, it will be noticed that the pin D extends transversely through the clamping block B to one side of the median line thereof so that the clamping block B can be readily used in conjunction with the clamp C on picker sticks of different width, by reversing the position of the clamping block B on the pin D whenever it is desired to change from a wider picker stick to a narrower picker stick. When the desired adjustment has been made the set screw E is locked in position by a jam nut E².

The ends of the pin D are connected by links F with a pivot G extending transversely through sweep straps H connected by a bolt I with the sweep stick J connected with the usual machinery for imparting the desired motion to the picker stick A, as hereinafter more fully explained. The pivot G extends through an elongated aperture K' formed in a striker K extending between the sweep straps H and adapted to abut against the outer edge of the picker stick A. The striker K is adapted to abut with its outer edge on an abutment L extending between the outer ends of the sweep straps H and secured thereto by transverse rivets, bolts or similar fastening devices. By the arrangement described the striker K is disposed intermediate the picker stick A and the abutment L and when the parts are in contact with each other, as shown in Fig. 3, then the pivot G is approximately midway between the ends of the slot K' and consequently the pivot G is relieved of all strain, which latter is taken up by the abutment L. The upper end of the striker K is connected with one end of a spring N, preferably in the form of an elastic webbing, attached at its outer end

to the outer end of the abutment L. By the use of the spring N the striker K readily swings out of engagement with the picker stick A at the time the sweep stick J has reached the end of its return movement to allow the picker stick A to readily swing back to its outermost position, as will be readily understood by reference to Fig. 1.

Although I have shown the links F, the 10 clamping block B and the clamp C disposed below the sweep straps H it is evident that the said parts may be located above the said sweep straps to accomplish the desired result. By the arrangement described the 15 straps H can be located higher up or lower down on the picker stick A to suit existing conditions, that is, according to the power to be exerted by the picker stick on the shuttle.

20 By the use of the striker K arranged as described a large bearing surface is had on the picker stick A to withstand the wear and to insure long life of the device. It will be noted that by the arrangement described the parts are connected with the picker stick A without weakening the latter by holes, notches or the like.

Having thus described my invention, I 30 claim as new and desire to secure by Letters Patent:

1. The combination of a picker stick, a sweep stick, straps extending from one end of the said sweep stick and between which the said picker stick extends, a striker extending between the said straps and mounted to swing thereon, a spring pressing the said striker, and a connection between the spring and said straps.

2. The combination of a picker stick, a 40 sweep stick, straps extending from one end of the said sweep stick and between which the said picker stick extends, a striker extending between the said straps and mounted to swing thereon, an abutment fixed between the outer end of the said straps for the striker to abut against, and a spring connecting the striker with the said abutment.

3. The combination of a picker stick, a sweep stick, straps extending from one end of the sweep stick and between which the said picker stick extends, an abutment fixed between the outer ends of the said straps, a striker between the said straps intermediate the said abutment and the picker stick, the 50 striker having an elongated slot formed therein, a pivot held on the straps and extending through the said slot for the said striker to swing on, and a spring connecting the striker with the abutment.

4. The combination of a picker stick, a 60 sweep stick, straps extending from one end of the sweep stick and between which the said picker stick extends, an abutment fixed between the outer ends of the said straps, a striker between the said straps intermediate 65 the said abutment and the picker stick, a pivot held on the straps for the said striker to swing on, and a spring connecting the upper end of the said striker with the said abutment.

5. The combination of a picker stick, a sweep stick, straps extending from one end of the sweep stick and between which the said picker stick extends, an abutment fixed between the outer ends of the said straps, a 75 striker between the said straps intermediate the said abutment and the picker stick, the said striker having an elongated aperture extending transversely therethrough, and a pivot held on the said straps and extending 80 through the said elongated aperture of the striker to relieve the pivot of strain at the time the striker is in contact with both the picker stick and the abutment.

6. The combination of a picker stick, a 85 sweep stick, straps extending from one end of the sweep stick and between which the said picker stick extends, an abutment fixed between the outer ends of the said straps, a striker between the said straps intermediate 90 the said abutment and the picker stick, the striker having an elongated slot, a pivot held on the straps and extending through the elongated slot for the said striker to swing on, and a spring connecting the striker with the abutment, a clamp attached to the picker stick, and links connecting the said clamp with the ends of said pivot.

7. The combination with a picker stick of a clamping block disposed upon the outer edge thereof and provided on both edges with projecting spurs for embedment in the picker stick to allow of reversing the clamping block, the said block having a transverse aperture to one side of the median line of the block, a pin extending through the said block aperture, a yoke connected with the said pin, and a set screw threaded through the yoke and bearing on the inner edge of the picker stick.

In testimony whereof I have signed my name to this specification in the presence of two subscribing witnesses.

WILLIAM H. KELLEY.
